(57) **CLAIM**

The ornamental design for a pair of mesh trim covers for a motorcycle horn, as shown and described.

DESCRIPTION

FIG. 1 is a top perspective view of a pair of mesh trim covers for a motorcycle horn, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and,

FIG. 10 is an enlarged detail view of area 10 in FIG. 7. The dash-dash broken lines showing the lettering in FIGS. 1 and 3 illustrate unclaimed portions of the pair of mesh trim covers for a motorcycle horn and form no part of the claimed design. The dash-dot broken lines depict the boundaries of the enlargement areas and form no part of the claimed design.
